X-RAY MACHINE

Oscar H. Pieper, Rochester, N. Y.

Application October 15, 1931, Serial No. 568,905

11 Claims. (Cl. 250—34)

My invention relates to X-ray machines and particularly to the mounting of the X-ray tube and to the immediately associated parts.

According to my invention I isolate the X-ray tube, in a metallic container, at a distance from the transformer, and the primary object of my invention is to provide an improved construction and arrangement wherein the X-ray tube is so mounted. Furthermore, in accordance with my invention, I mount the filament control rheostat directly at the cathode end of the X-ray tube, and it is a further object of my invention to provide improved means for so mounting the rheostat and an improved construction for the rheostat itself.

The metallic container to which I have referred is grounded and the problems of high voltage isolation are met so that appropriate safety in handling is assured; and the mechanical construction and arrangement are such that easy manipulation of the tube is possible.

My invention is illustrated in the accompanying drawings in which:

Figure 1 is a plan view of the structure; Figure 2 is a central vertical sectional view thereof, taken on the plane of the line 2—2 of Figure 1 and looking in the direction indicated by the arrows;

Figure 3 is, in the main, a side elevational view, part however being shown in section taken on the plane of the line 3—3 of Figure 2, looking in the direction indicated by the arrows;

Figure 4 is a partial vertical cross sectional view, taken on the plane of the line 4—4 of Figure 2 and looking in the direction indicated by the arrows, with the X-ray tube removed;

Figure 5 is a partial sectional view taken on the plane on which Figure 2 is taken, this figure showing the collector and wiper arrangement, which will be referred to, on an enlarged scale;

Figure 6 is a view similar to Figure 2 showing a modification;

Figure 7 is a sectional view taken on the plane on which Figure 2 is taken, this view showing the rheostat on larger scale and in greater detail;

Figure 8 is a cross sectional view taken on the plane of the line 8—8 of Figure 7 and looking in the direction indicated by the arrows; and

Figure 9 is a cross sectional view taken on the plane of the line 9—9 of Figure 7 and looking in the direction indicated by the arrows.

I shall first refer to Figures 1 to 5, inclusive.

A metal tube 10, which is grounded, is mounted in a split ring 11, part of a bracket 12 which, in turn, is supported in any suitable way. The

members of the split ring are held together by appropriate screws 13. The tube 10 may occupy any position, vertically, in the split ring 11, as convenience may dictate. At its bottom, the tube 10 carries the threaded metallic collar 14 which is adapted to receive the internally threaded union 15. A tube 16 of insulating material fits inside the metallic tube 10 and is coextensive therewith at the top. At the bottom, the insulating tube 16 extends beyond the metallic tube 10 as shown. A metallic sleeve 17 is slipped over the protruding end of the insulating tube 16, this sleeve having a flange 18 engaging within the union 15 against its internal shoulder. The union 15 engages the bead 19 on the sleeve 14 15 so that it will not clamp the flange 18 tightly, leaving it sufficiently free for the sleeve 17 to turn on the insulating tube 16.

The free end of the sleeve 17 is threaded for the reception of the rim 20 on the central part of the container or housing for the X-ray tube. The nature of this central part of the container or housing for the X-ray tube will be best understood by referring first to Figure 4. This central part, designated generally by the reference character 21, is in the form of a metallic skeleton embodying rings 22, 22, on opposite sides, and a seat or saddle 23, against which the X-ray tube may rest, with its ends extending through the rings. The X-ray tube is shown at 24 and, in the specific instance shown, is the type of tube wherein the central portion is a chrome iron ring welded into the inner ends of the tube glass tubular portions 25. This chrome iron ring is surrounded by a layer of lead, surrounded in turn by a brass supporting ring 26, and this brass supporting ring rests directly in the seat or saddle 23, being mounted therefor rotation. The form of the central part 21 is such as to leave the central opening or slot 27, through which the focusing device extends as will be pointed out presently, the tube being held upon the seat or saddle 23 by means of the angular side plates 28, 28 which close the central part 21 and define the opening or slot 27. These side plates hold the X-ray tube in place, springs 29, 29 intervening between the flanges on the side plates and the X-ray tube in order that the latter may be appropriately cushioned. The supporting ring 26 of the tube carries the radially extending tubular portion 30 (Figure 3), indicated by the circle 50 in Figure 2, this tubular portion carrying the focusing device 31, as shown in Figure 3. As will be seen from Figure 4, the form of the central part 21 is such, and the length of the slot 27 is such, that the focusing device is capable of being 55

swung, from the position shown in Figure 3, approximately 30° above horizontal and down to a vertical position. The general form of the central part 21, below the rim 20, and the manner of supporting the X-ray tube therein, is shown and described in my co-pending application Serial No. 502,366 filed December 15, 1930, now Patent No. 1,949,760, issued March 6, 1934.

Metallic housing portions 32, 32 are mounted on 10 the rings 22, 22, extending outwardly therefrom and completing the container for the tube, as shown in Figures 1 and 2. Tubes 33, 33 of insulating material surround the respective ends of the X-ray tube beyond the seat or saddle within 15 the metallic housing or container. These tubes 33, may be of any suitable insulating material possessing adequate strength and rigidity and may be made either of single tubing or of a plurality of tubes one slipped within the other. They are 20 supported in the rings 22, at the bottom, by means of screws 34, 34 passing through the bottom of the rings and threading into ferrules 35 fixed in the tubes, as shown in Figure 2.

The anode end of the X-ray tube is provided 25 with radiator fins 36 which are housed by having cup 37 and the hemispherical cap 38. This cap presents a spherical inner surface which is wiped by a contact member 39 carried on the end of a copper tube 40 which will be referred to further 30 presently, access to the interior of the tube 33 being gained by way of the opening 33a. This contact member 39 preserves its contact with the cap 38 as the X-ray tube is rotated about its own axis in the movement of the focusing device 31, 35 the cap being in direct connection with the anode terminal as shown.

The arrangement at the cathode end of the tube will be described later. Suffice it to say for the present that two conductors lead thereto, one 40 a copper tube 41, similar to the copper tube 40, the other an insulated wire 42 within it, access to the interior of the tube 33 being gained through the opening 33b.

The central part 21 of the housing has an internal shoulder 43 within it at the bottom of the rim 20, as shown in Figures 2 and 4. On this shoulder, within the rim 20, is an insulating block 44 held in fixed position by the set screw 45. A tube 46 of insulating material is disposed 45 concentrically within tube 16, lying between the insulating block 44 and the grounded metallic cover 47 at the upper end which closes the top of the metallic tube 16, this cover 47 being provided with an annular groove 48 to receive the upper end of the insulating tube 46. The cover 47 is provided 50 with ventilating openings 47a and, internally of the tube 16, with a downwardly extending lip 49. A screw 50 extends through the metallic tube 16 and the insulating tube 46 into this lip, holding 55 these three elements in rigid relation. A tube 51 of insulating material surrounds the copper tube 40, from the point where it enters the tube 33, passing toward the center of the structure and then upwardly through the insulating block 44. 60 The opening in the insulating block 44 through which the tubing 51 passes is at the side of the block and it is of such size that the tubing 51 fits tightly within it, then passing upwardly into the space between the insulating tube 16 and the insulating tube 46. On the opposite side of the 65 insulating block 44 an insulating post 52 rises into the space between the insulating tube 16 and the insulating tube 46, and an annular metallic crown 53, of inverted U-shaped cross section, 70 is mounted on the top of the tubing 51 and the

post 52 in the annular space between the insulating tube 16 and the insulating tube 46. This crown is a collector and the upper end of the copper tube 40 is connected electrically with the crown on the tubing 51, interiorly, by means of the small conductor 54.

A liner 55 of insulating material is tightly fitted into the insulating tube 16 in the zone of the collector 53 and a sleeve 56 is tightly fitted on the insulating tube 46 in horizontal register there- 10 with.

The cover 47 is provided with an opening 57 in register with the space between the insulating tube 16 and the insulating tube 46. A boss member 58, surrounding this opening, is secured 15 on the top of the cover 47 by means of screws 59, 59. A tube 60 of insulating material has its upper end threaded into the boss member 58 and it extends downwardly through the opening 57 into the space between the insulating tube 16 and the insulating tube 46. A plug 61 is screwed in the bottom of the tube 60, this plug having a flange 62 resting on the shoulders formed by the tops of the liner 55 and sleeve 56, this plug extending down into the space between the liner 25 and the sleeve. The plug 61 is provided with a central bore 63 in which a plunger 64 is slidably disposed, this plunger being pressed downwardly by means of a helical spring 65 located in the bore between the plunger and the metallic screw 30 plug 66. This is best shown in Figure 5. The plunger 64 carries the downwardly extending stem 67 which terminates in the spherical head 68, this head engaging in an annular groove or depression 69 in the top of the collector 53. The 35 element 64, 67, 68 is of metal and constitutes a wiper for constant engagement with the collector 53. The spring 65 is of course of metal and through it electrical connection from the collector 53 to the plug 66 is effected.

A metal armored cable 70, the outer metal sheath of which is grounded, leads from within the tube 60 outwardly through the boss member 58, for connection to the transformer. The insulated conductor 71 within this cable 70 is connected 45 with the metallic plug 66 as shown in Figure 2. Thus the anode end of the X-ray tube is connected with the distant transformer by way of the cap 38, wiper 39, copper tube 40, conductor 44, collector 53, wiper 64, 67, 68, spring 65, plug 50 66, and protected conductor 71. The boss member 58 may be extended to any length desired and any suitable clamping means may be provided between this boss member and the cable 70.

A boss member 72, similar to the boss member 55 55, is secured on the top of the cover 47, by means of screws 73, 73, in register with a central opening 74 in the cover, which opening, in turn, is in register with the insulating tube 46. A tube 75 of insulating material has its upper end screwed 60 into the boss member 72 and its lower end has threaded thereto a plug 76 of insulating material which fits in the tube 46. This plug carries two wipers 77 and 78, each constructed precisely as the wiper arrangement in the plug 61. A metal 65 armored cable 79, containing two insulated conductors, extends from within the tube 75 out through the boss member 72 to the distant transformer. This cable, like the cable 70, has its outer metal sheath grounded and its two conductors 70 are respectively connected with the metallic screw plugs 77a and 78a of the wipers 77 and 78 respectively. The boss member 72 may be extended as desired and provided with suitable means for clamping the cable, as in the case of 75

the other boss member and cable which has been described. The wipers 77 and 78 form part of the filament circuit, and that will now be described.

5 A copper tube 41 is encased in insulating tubing 80, this tubing extending upwardly through a central opening in the insulating block 44. It is tightly held in that opening, then passing upwardly into the insulating tube 46. At its top 10 it is provided with a metallic thimble 80' which has an annular depression or groove 81 in its top. The spherical head of the wiper 78 rides in this depression or groove, in constant engagement with the thimble. A central contact member 82 is mounted in the thimble, but insulated therefrom by means of the bushing 83 and the disc 84. This is best shown in Figure 5. The copper tube 41 extends out of the top of the insulating tubing 80 and is connected with the 15 central contact member 82 by means of the short conductor 85. The insulated conductor 42, which lies within the copper tube 41, extends laterally through slots 86 and 87 in the ends of the tube 41 and tubing 80 respectively and is electrically 20 connected with the thimble 80' at 88.

It will now be clear that the wiper 77 lies axially in the metallic tube 10. It will also be clear that the X-ray tube housing is rotatable, within reasonable limits, about this axis, this rotation taking place between the X-ray tube housing and the relatively fixed tube 10. The central part 21 of the X-ray tube housing is carried from the sleeve 17 which, as has been described, is capable of rotation in the union 15 about the insulating tube 16. Since the insulating block 44 is one of the elements in fixed relation to the central part 21 of the housing, it rotates with the housing and, with it, the rising insulating tubings 51 and 80 and the parts carried thereby. This means that the collectors 53 and 80' rotate with the X-ray tube housing while wipers in the plugs 61 and 76 remain stationary with the tube 10. As this relative rotation takes place, the wiper 64, 67, 68 engages the collector 53 at all 25 times, the wiper 78 engages the thimble 80' at all times, and the wiper 77 engages the central contact member 82 at all times, these wipers being spring pressed, as has been described, to insure appropriate engagement.

50 I shall now refer to the modification illustrated in Figure 6. In this modification the rotation of the X-ray tube housing, relative to the metallic tube 10 is accommodated in another way than that hereinbefore described. In this modification the central part 21a is analogous to the central part 21 of the structure shown in the preceding figures. The housing portions 32a, 32a are the same as the housing portions 32, 32, and the X-ray tube arrangement within the housings 60 of the two structures are identical, so description of these parts in Figure 6 will not be necessary.

The central part 21a differs from the part 22 in that it is not formed at the top for an insulating block such as the insulating block 44 of Figure 2.

75 The metallic tube 10a of Figure 6 corresponds to the metallic tube 10 of Figure 2. The insulating tube 16a corresponds to the insulating tube 16 except that, as shown in the Figure 6, it extends downwardly a greater distance, as indicated at 16b. The collar 14a, the union 15a and the sleeve 17a are substantially the same as the parts 14, 15 and 17, but it may be noted here that a packing ring 15b may be provided between the flange on

the sleeve 17a and the collar 14a if desired. The bracket 12a corresponds to the bracket 12.

At the top of the metallic tube 10a, the cover 47b is provided, this cover having one or more ventilating openings 47c. This cover 47b is provided with openings 57a and 74a at opposite sides thereof, these openings being of such size as just to accommodate the cables 89 and 90, respectively. The cable 89 is flexible and leads from the wiper 39a of the anode terminal of the X-ray tube first into the central portion 21a of the housing, then upwardly into and through the insulating tube 16a and out through the opening 57a, from whence it is led to the distant transformer as in the case of the previously described form of my invention. This cable contains a single conductor 40a. The cable 90 is flexible and leads from the cathode end of the X-ray tube, first into the central part 21a of the housing and then upwardly into and through the insulating tube 16a and out through the opening 74a to the distant transformer. This cable contains the two conductors 41a and 42a.

The housing 21a, 32a has rotary motion relative to the tube 10a, as in the case of the housing and tube of the structure previously described. In this instance, however, instead of using collectors and wipers, the movement is accommodated, so far as electrical connections are concerned, by the flexibility of the cables 89 and 90 between the cover 47b and the respective ends of the X-ray tube, these points at which the cables are anchored being sufficiently far apart to permit the cables to accommodate themselves to the relative motion between their ends and the places where they pass through the cover.

The openings 57a and 74a in the cover 47b are surrounded by boss members 58a and 72a, respectively, and beyond these members the cables 89 and 90 are protected by a grounded metal armor 40 as indicated at 89a and 90a. This form of my invention makes for simplicity of construction and is particularly apt when the tubes 10a and 16a are made rather long.

I shall now describe the arrangement at the 45 cathode end of the X-ray tube, by reference to Figures 7, 8 and 9. The cathode end of the tube is formed with a depression 91 and is provided with a metallic cap 92 which follows the form of the end of the tube, as illustrated in Figure 7. 50 In the depression in the cap, a metal annulus 93 is provided, this annulus being clamped in place by means of an insulated central post 94 which has a flange 95 and a screw threaded stem 96 at the other end for the reception of a nut 97. The 55 post 94 is insulated from the annulus 93 and the cap 92 by means of the insulating sleeve 98 and the insulating disc 99. A washer 100 is interposed between the disc 99 and the nut 97. The sleeve 98 has a flange 101 which engages the face 60 of the annulus 93 and it will be seen how the flange 95 and the flange 101 cooperate to assemble the arrangement which has just been described in proper relation when the nut 97 is drawn up. The cap 92 is connected with one end of the X-ray 65 tube filament by means of the conductor 102 and the post 94 is connected with the other end of the filament by means of the conductor 103 which is clamped against the nut 97 by means of the nut 104. It will be remembered that this X-ray tube 70 is rotatable on its own axis and the central position of the post 94 is important in this connection as will appear presently.

A block of insulating material 105 is mounted within the insulating tube 33 just beyond the 75

cathode end of the X-ray tube. The upper half of this block is of cylindrical form to fit the interior of the tube 33 and it is held in the tube by means of the screws 106, 106. An arch 107 of insulating material is secured to the lower side of the block 105 by means of screws 108, 108. A resistance wire 109 is wound on this arch, one end thereof taking under the head of the screw 110 which also receives and clamps the end of the conductor 41b which leads from the copper tube 41 through an opening 41c in the block 105. The other end of the resistance wire 109 is clamped by the dead screw 111. Centrally disposed in the insulating block 105 is the metal tube 112 which is firmly lodged in the block. This tube has the internal shoulder 113 against which a plug 114 rests. This tube also contains the plunger 115 which has the stem 116 extending outwardly of the tube 112 toward the X-ray tube. This stem 116 carries the spherical head 117 which rests in a depression 119 in the post 94. A helical spring 120 lies between the plug 114 and the plunger 115 so as to urge the head 117 against the post 94 for the purpose of constant electrical contact. A stem 121 is fixed in the plug 114, passes through the helical spring 120 and into a bore in the plunger 115, this stem contributing to the maintenance of the proper alignment of the stem 116 and the head 117. A sleeve 122 surrounds and is rotatable on the tube 112. A wiper 123 is carried on the sleeve 122, and a nut 124, on the end of the tube 112, holds the sleeve and wiper in any adjusted position, a washer 125 intervening. This wiper engages the coiled resistance wire, as shown in Figure 9, and may be moved to any position over the coil of wire so as to include more or less of the resistance wire in the circuit. The tube 112 also carries the cap 126 which is secured to the end thereof by means of the screw 127. This cap is a protection against discharge between the adjacent X-ray tube terminal and the metallic housing 32 or 32a. It is provided with a semi-cylindrical appendage 128 which forms a shield about the resistance coil.

The insulating block 105 also has firmly lodged therein the metallic tube 129 the interior arrangement of which is substantially the same as that of the tube 112. The wiper 130 engages an annular groove 131 in the face of the annulus 93, this groove 131 being concentric with the axis of the tube. The spring within the tube 129 maintains the spherical head of the wiper 130 always in appropriate contact in the groove 131. The end of the conductor 42 is connected with the end of the tube 129 by means of a screw 132, this conductor 42 passing through the opening 41c.

By the arrangement described, the conductors 41 and 42 are in constant connection with the filament of the X-ray tube and the rheostat winding 109 and wiper 123 are included in this circuit.

65 I claim:

1. In X-ray apparatus, a metallic tubular member, a metallic housing carried by and swiveling on said tubular member, an X-ray tube mounted in said housing, conductors leading from the terminals of said X-ray tube into one end and through and out of the other end of said tubular member, said conductors being held at said other end of said tubular member and beyond the same being sheathed in a metallic armor.

2. In X-ray apparatus, a metallic tubular member, a metallic housing carried by and swiveling on said tubular member, a metallic cover on the end of said tubular member, an X-ray tube mounted in said housing, and flexible conductors leading from the terminals of said X-ray tube to and through said tubular member and openings in said cover.

3. In X-ray apparatus, a metallic tubular member, a metallic housing carried by and swiveling on said tubular member, a metallic cover on the end of said tubular member, an X-ray tube mounted in said housing, and flexible conductors leading from the terminals of said X-ray tube to and through said tubular member and openings in said cover, said conductor beyond said cover being sheathed in a metallic armor.

4. In X-ray apparatus, a tubular supporting member, a housing carried by and swiveling on said supporting member, an X-ray tube mounted in said housing, conductors leading from the terminals of said X-ray tube into one end of said supporting member, conductors leading from the other end of said supporting member, and collectors and wipers in said supporting member connecting said first-named with said last-named conductors.

5. In X-ray apparatus, a metallic tubular supporting member, a metallic housing carried by and swiveling on said supporting member, an X-ray tube mounted in said housing, conductors leading from the terminals of said X-ray tube into one end of said supporting member, conductors leading from the other end of said supporting member, and collectors and wipers in said supporting member connecting said first-named with said last-named conductors, said last-named conductors beyond said supporting member being sheathed in metallic armors.

6. In an X-ray apparatus, a tube, a housing carried by and swiveling relative to said tube, an X-ray tube mounted in said housing, an insulating block at the bottom of said tube fixed relative to said housing, cables leading from the terminals of said X-ray tube upwardly through said block into said tube, a collector at the upper end of each said cable, corresponding cables leading down into said tube, and wipers with which said last-named cables are connected engaging said collectors.

7. In an X-ray apparatus, a tube, a housing carried by and swiveling relative to said tube, an X-ray tube mounted in said housing, an insulating block at the bottom of said tube fixed relative to said housing, a second tube co-axially arranged in said first-named tube, a cable leading from one end of said X-ray tube through said block into said second tube, a cable leading from the other end of said X-ray tube through said block into the space between said first-named tube and said second tube, a collector at the end of each cable, and corresponding cables leading respectively down into said second tube and down into the space between said first-named tube and said second tube, and wipers at the ends of said last-named cables engaging said collectors.

8. In an X-ray apparatus, a tube, a housing carried by and swiveling relative to said tube, an X-ray tube mounted in said housing, an insulating block at the bottom of said tube fixed relative to said housing, a second tube co-axially arranged in said first-named tube, a double conductor cable leading from the cathode end of said

X-ray tube through said block into said second tube, a single conductor cable leading from the other end of said X-ray tube through said block into the space between said first-named tube and said second tube, a contact crown on the end of said first-named cable, an insulated central contact member carried by said crown, said crown and said contact member being electrically connected respectively with the conductors of said first-named cable, an annular collector lying in said space between said first-named tube and said second tube, said collector being mounted upon the end of said second-named cable and electrically connected with the conductor thereof, a plug in said second tube, spring pressed wipers carried by said plug and engaging said crown and said central contact member respectively, a plug in said space between said first-named tube and said second tube, a spring pressed wiper carried by said second-named plug, and corresponding cables respectively entering said second tube and said space between said first-named tube and said second tube and having their conductors electrically connected with said wipers respectively.

9. In X-ray apparatus, a tubular member, a cover on one end thereof, a housing carried by and swiveling on the other end of said tubular

member, an X-ray tube mounted in said housing, and flexible cables leading loosely from the respective terminals of said X-ray tube to said cover and held in openings therein, said cables passing out through said openings.

5

10. In X-ray apparatus, a metallic tubular member, a metallic cover on one end thereof, a metallic housing carried by and swiveling on the other end of said tubular member, an X-ray tube mounted in said housing, and flexible cables leading loosely from the respective terminals of said X-ray tube to said cover and held in openings therein, said cables passing out through said openings and being sheathed in metallic armors therebeyond.

15

11. In an X-ray apparatus, a metallic housing, an X-ray tube mounted within the housing, insulating tubes within and fixed to the housing and surrounding the ends of the X-ray tube, a rheostat within and secured to one of the insulating tubes in proximity to the cathode end of the X-ray tube and connected in circuit with the filament of said X-ray tube, and a metallic shield within said insulating tube and in proximity to the outer side of said rheostat.

25

OSCAR H. PIEPER.
